5 Claims

ABSTRACT OF THE DISCLOSURE

The invention provides new fluorescent compounds of the formula

wherein either

- (a) one, two or three of the symbols R₁, R₂, R₃ or R₄ represent halogen atoms of the group fluorine, chlorine or bromine, whilst the remainder of these symbols denote hydrogen, or
- (b) one or two of the symbols R₁, R₂, R₃ or R₄ represent a halogen atom of the group fluorine, chlorine or bromine, whilst another of the symbols R₁, R₂, R₃ or R₄ denotes an alkyl group with 1 to 4 carbon atoms or an alkoxy group with 1 to 4 carbon atoms, or two of the symbols mentioned together represent a methylenedioxy group, and the remaining symbols denote hydrogen.

The defined compounds are valuable optical brightening agents especially for polyamides polyvinyl chloride and polystyrene.

The present invention relates to selected distyryl compounds of diphenyl, processes for their manufacture, and their use as optical brighteners for organic materials.

The new compounds are symmetrically substituted relative to the diphenyl grouping and correspond to the formula

wherein either

- (a) one, two or three of the symbols R₁, R₂, R₃ or R₄ represent halogen atoms of the group fluorine, chlorine or bromine, whilst the remainder of these symbols denote hydrogen, or
- (b) one or two of the symbols R₁, R₂, R₃ or R₄ represent a halogen atom of the group fluorine, chlorine or bromine, whilst another of the symbols R₁, R₂, R₃ or R₄ denotes an alkyl group with 1 to 4 carbon atoms or an alkoxy group with 1 to 4 carbon atoms, or two of the symbols mentioned together represent a methylenedioxy group, and the remaining symbols denote hydrogen.

2

enedioxy group, and the remaining symbols denote hydrogen.

Compounds of preferred importance within the framework of the above definition are those of the following formulae:

wherein either

- (a) one, two or three of the symbols R_{1'}, R_{2'}, R_{3'} and R_{4'} represent halogen atoms of the group fluorine, chlorine or bromine, whilst the remainder of these symbols denote hydrogen, or
- (b) one of the symbols R_{1'}, R_{2'}, R_{3'} or R_{4'} represents a halogen atom of the group fluorine, chlorine or bromine whilst another of the symbols R_{1'}, R_{2'}, R_{3'} or R_{4'} denotes an alkyl group with 1 to 4 carbon atoms, a methoxy group of an ethoxy group, or two of the symbols mentioned together represent a methylenedioxy group, and the remaining symbols denote hydrogen;

wherein either

- (a) two or three of the symbols R_{1''}, R_{2''}, R_{3''} and R_{4''} represent halogen atoms of the group fluorine, chlorine or bromine, whilst the remainder of these symbols denote hydrogen, or
- (b) one of the symbols R_{1''}, R_{2''}, R_{3''} or R_{4''} represents a halogen atom of the group fluorine, chlorine or bromine whilst another of the symbols R_{1''}, R_{2''}, R_{3''} or R_{4''} denotes an alkyl group with 1 to 4 carbon atoms or an alkoxy group with 1 to 4 carbon atoms, or two of the symbols mentioned together represent a methylenedioxy group and the remaining symbols denote hydrogen.

wherein two or three of the symbols R₅, R₆, R₇ and R₈ represent a halogen atom from the group fluorine, chlorine or bromine, whilst the remaining symbols denote hydrogen.

The compounds of the formula

(3)

wherein X denotes a halogen atom, preferably chlorine or fluorine, are of particular practical interest. It has been found that these compounds are particularly suitable for the bulk brightening of polyamides, polyvinyl chloride and polystyrene when shaping these substrates at high temperatures, that is to say temperatures above 150° C., preferably up to about 320° C. From previous experience it was surprising that these compounds should display sufficient heat stability on processing at high temperatures.

Very suitable compounds are, for example, those of the formula

(3a)

wherein the chlorine indicated in the formula is preferably in position 2.

The compounds defined above can be manufactured analogously to processes which are in themselves known. A preferred procedure is to react, in a molecular ratio of 1:2, compounds of the formula

(4)

with compounds of the formula

(5)

wherein, in these formulae, R₁, R₂, R₃ and R₄ have the above-mentioned meaning and one of the symbols Z₁ and Z₂ denotes a O=CH— group and the other denotes one of the groupings of the formulae

wherein R represents an optionally substituted alkyl radical (preferably with up to 6 C atoms), an optionally substituted phenyl radical, a cyclohexyl radical or an aralkyl radical.

Accordingly, it is for example possible to react 1 mol equivalent of the dialdehyde of the formula

(6)

with two mol equivalents of a monofunctional compound of the formula

(7)

or to react one mol equivalent of a compound of the formula

(8)

with 2 mol equivalents of an aldehyde of the formula

(9)

wherein V denotes a substituent of the formulae (5a) to (5d). The compounds according to formulae (1a), (1b), (2), (3) and (3a) are manufactured entirely analogously.

The reaction is in both cases carried out by allowing the components to react in the presence of a strongly basic alkali compound and in the presence of a preferably hydrophilic, strongly polar solvent, and in the case where alkali hydroxides are used as the strongly basic alkali compound, these alkali hydroxides can contain up to 25% of water.

Toluene, xylene, chlorobenzene or alcohols such as, for example, ethanol, ethylene glycol monomethyl ether, and also N-methylpyrrolidone, diethylformamide, dimethylacetamide and preferably dimethylformamide or dimethylsulphoxide, may, for example, be mentioned as solvents for the process described above for the manufacture of compounds of the formula (1).

The temperature at which the reaction is carried out can vary within wide limits. It is determined (α) by the stability to the reactants of the solvent used, especially to the strongly basic alkali compounds, (β) by the reactivity of the condensation components and (γ) by the effectiveness of the solvent-base combination as a condensation agent. Preferably the temperature lies approximately in the range of 30 to 60° C., but in many cases satisfactory results are already achievable at room temperature (about 20° C.) on the one hand, or, on the other, at temperatures of 100° C., and even at the boiling point of the solvent, if this is desired for reasons of saving time or employing a less active but cheaper condensation agent. In principle, reaction temperatures in the range of 10 to 180° C. are thus also possible.

Strongly basic alkali compounds which can be used are above all the hydroxides, amides and alcoholates (preferably those of primary alcohols containing 1 to 4 carbon atoms) of the alkali metals, and for economic reasons those of lithium, sodium and potassium are of predominant interest. In principle, and in special cases, it is however also possible successfully to use alkali sulphides and alkali carbonates, arylalkali compounds, such as, for example, phenyl-lithium, or strongly basic amines (including ammonium bases, for example trialkylammonium hydroxides).

The new compounds defined above possess a more or less pronounced fluorescence in the dissolved or finely divided state. They can be used for the optical brightening of the most diverse synthetic, semi-synthetic or natural organic materials or substances which contain such organic materials.

The following groups of organic materials, where optical brightening thereof is relevant, may be mentioned as examples of the above, without the survey given below being intended to express any restriction thereto:

(I) Synthetic organic high molecular materials:

(a) Polymerisation products based on organic compounds containing at least one polymerisable carbon-carbon double bond, that is to say their homopolymers or copolymers as well as their after-treatment products such as, for example, cross-linking, grafting or degradation products, polymer blends, products obtained by modification of reactive groups, and the like, for example polymers based on α,β -unsaturated carboxylic acids or derivatives of such carboxylic acids, especially on acrylic compounds (such as, for example, acrylic esters, acrylic acid, acrylonitrile, acrylamides and their derivatives or their methacryl analogues) and polymers based on vinyl and vinylidene compounds (such as, for example, vinyl alcohol),

(b) Polymerisation products such as are, for example, obtainable by ring opening, for example, polyamides of the polycaprolactam type, and also polymers which are obtainable both via polyaddi-

- tion and via polycondensation, such as polyethers or polyacetals,
- (c) Polycondensation products or precondensates based on bifunctional or polyfunctional compounds possessing condensable groups, their homocondensation and co-condensation products, and after-treatment products, such as, for example, polyamides (for example hexamethylenediamine adipate), maleate resins, melamine resins, their precondensates and analogues, polycarbonates and silicones,
- (d) Polyaddition products such as polyurethanes (crosslinked and non-crosslinked) and epoxide resins.
- (II) Semi-synthetic organic materials such as, for example cellulose esters of varying degrees of esterification (acetate or triacetate) or cellulose ethers, regenerated cellulose (viscose or cuprammonium cellulose), or their after-treatment products, and casein plastics.
- (III) Natural organic materials of animal or vegetable origin, for example based on cellulose or proteins, such as cotton, wool, linen, silk, natural lacquer resins, starch and casein.
- The organic materials to be optically brightened can be in the most diverse states of processing (raw materials, semi-finished goods or finished goods). On the other hand, they can be in the form of structures of the most diverse shapes, say for example predominantly three-dimensional bodies such as sheets, profiles, injection mouldings, various machined articles, chips, granules or foams, and also as predominantly two-dimensional bodies such as films, foils, lacquers, coatings, impregnations and coatings, or as predominantly one-dimensional bodies such as filaments, fibres, flocks and wires. The said materials can, on the other hand, also be in an unshaped state, in the most diverse homogeneous or inhomogeneous forms of division, such as, for example, in the form of powders, 35 solutions, emulsions, dispersions, latices, pastes or waxes and the like.
- Fibre materials can, for example, be in the form of endless filaments (stretched or unstretched), staple fibres, flocks, hanks, textile filaments, yarns, threads, fibre fleeces, felts, waddings, flock structures or woven textile fabrics, 40 textile laminates, knitted fabrics and papers, cardboards or paper compositions, and the like.
- The compounds to be used according to the invention are of importance, *inter alia*, for the treatment of organic textile materials, especially woven textile fabrics. Where 45 fibres, which can be in the form of staple fibres or endless filaments or in the form of hanks, woven fabrics, knitted fabrics, fleeces, flock substrates or laminates, are to be optically brightened according to the invention, this is advantageously effected in an aqueous medium, wherein the compounds in question are present in a finely divided form, suspensions or possibly solutions. If desired, dispersing agents, stabilisers, wetting agents and further auxiliaries can be added during the treatment. Depending on the type of brightener compound used, it may prove advantageous preferably to carry out the treatment in a neutral or alkaline or acid bath. The treatment is usually carried out at temperatures of about 20 to 140° C., for example at the boiling point of the bath or near it (about 50 90° C.). Solutions or emulsions in organic solvents can also be used for the finishing, according to the invention, of textile substrates, as is practised in the dyeing trade in so-called solvent dyeing (pad-thermofix application, or exhaustion dyeing processes in dyeing machines).
- The new optical brighteners according to the present invention can further be added to, or incorporated in, the materials before or during their shaping. Thus they can for example be added to the compression moulding composition or injection moulding composition during the manufacture of films, foils or mouldings.
- Where fully synthetic or semi-synthetic organic materials are being shaped by spinning processes or via spinning compositions, the optical brighteners can be applied in accordance with the following processes:
- 5 5 6
- 5 Addition to the starting substances (for example monomers) or intermediates (for example precondensates or prepolymers), that is to say before or during the polymerisation, polycondensation or polyaddition,
- 10 Powdering onto polymers chips or granules for spinning compositions,
- 10 Bath dyeing of polymer chips or granules for spinning compositions,
- 10 Metered addition to spinning melts or spinning solutions, and
- 15 Application to the tow before stretching.
- 15 The new optical brighteners according to the present invention can, for example, also be employed in the following use forms:
- 20 (a) Mixed with dyestuffs (shading) or pigments (for example white pigments), or as an additive to dye baths, printing pastes, discharge pastes or reserve pastes, or for the after-treatment of dyeings, prints or discharge prints.
- 25 (b) Mixed with so-called "carriers," wetting agents, plasticisers, swelling agents, anti-oxidants, light protection agents, heat stabilisers and chemical bleaching agents (bleaching bath additives).
- 30 (c) Mixed with crosslinking agents or finishes (for example starch or synthetic finishes), and in combination with the most diverse textile finishing processes, especially synthetic resin finishes (for example creaseproof finishes such as "wash-and-wear," "permanent-press" or "no-iron"), as well as flameproof finishes, soft handle finishes or antistatic finishes, or antimicrobial finishes.
- 35 (d) Incorporation of the optical brighteners into polymeric carriers (polymerisation, polycondensation or polyaddition products), in a dissolved or dispersed form, for use, for example, in coating compositions, impregnated compositions or binders (solutions, dispersions and emulsions) for textiles, fleeces, paper and leather.
- 40 (e) As additives to so-called "master batches."
- 45 (f) As additives to the most diverse industrial products in order to render these more marketable (for example improving the appearance of soaps, detergent, pigments and the like).
- 45 (g) In combination with other optically brightening substances.
- 50 (h) In spinning bath preparations, that is to say as additives to spinning baths such as are used for improving the slip for the further processing of synthetic fibres, or from a special bath before the esterification of the fibre.
- 55 (i) As scintillators for various purposes of a photographic nature, such as, for example, for electrophotographic reproduction or supersensitisation.
- 60 If the brightening process is combined with textile treatment methods or finishing methods, the combined treatment can in many cases advantageously be carried out with the aid of appropriate stable preparations, which contain the optically brightening compounds in such concentration that the desired brightening effect is achieved.
- 65 In certain cases, the brighteners are made fully effective by an after-treatment. This can, for example, represent a chemical treatment (for example acid treatment), a thermal treatment (for example heat) or a combined chemical/thermal treatment. Thus, for example, the appropriate procedure to follow in optically brightening a series of fibre substrates with the brighteners according to the invention is to impregnate these fibres with the aqueous dispersions or solutions of the brighteners at temperatures below 75° C., for example at room temperature, and to 70 75 subject them to a dry heat treatment at temperatures

above 100° C., it being generally advisable additionally to dry the fibre material beforehand at a moderately elevated temperature, for example at not less than 60° C. and up to about 130° C. The heat treatment in the dry state is then advantageously carried out at temperatures between 120 and 200° C., for example by heating in a drying chamber, by ironing within the specified temperature range or by treatment with dry, superheated steam. The drying and dry heat treatment can also be carried out in immediate succession or be combined in a single process stage.

The amount of the new optical brighteners to be used according to the invention, relative to the material to be optically brightened, can vary within wide limits. A distinct and durable effect is already achievable with very small amounts, in certain cases, for example, amounts of 0.0001 percent by weight. However, amounts of up to about 0.8 percent by weight and above can also be employed. For most practical purposes, amounts between 0.0005 and 0.5 percent by weight are of preferred interest.

In the examples, the parts, unless otherwise stated, are always parts by weight and the percentages are always percentages by weight. Unless otherwise stated, melting points and boiling points are uncorrected.

EXAMPLE 1

A solution of 79.6 g. of 4,4'-bis-(dimethoxyphosphonomethyl)-diphenyl of the formula

and 57.4 g. of 2-chlorobenzaldehyde (98% strength) in 300 ml. of anhydrous dimethylformamide, warmed to approx. 60° C., is added dropwise, over the course of 20 minutes, to a suspension of 26.2 g. of sodium methylate (98.8% strength) in 200 ml. of anhydrous dimethylformamide, with good stirring. In the course thereof, the reaction temperature rises from 23° C. to 45° C., and provision is made, by cooling with icewater, that this temperature is not exceeded. The pale yellow suspension is stirred for a further 2 hours at 40 to 45° C., cooled to room temperature, diluted with 330 ml. of desalinated water and cooled to 5° C., and the product which crystallises out is filtered off, washed with about 2.5 litres of desalinated water until the wash water reacts neutral, and dried in vacuo at 100 to 110° C.

84.4 g. (98.8% of theory) of the compound of the formula

are obtained as a light yellow crystal powder of melting point 196.5 to 199° C. Recrystallisation thereof from toluene yields 56.8 g. (67.3% of theory) of a pale yellow crystal powder of melting point 209 to 210° C. After repeated recrystallisation from toluene, the melting point is 211 to 212° C.

Instead of the 4,4'-bis-(dimethoxyphosphonomethyl)-diphenyl of the formula (10) used above, the equivalent amount of 4,4'-bis-(diethoxyphosphonomethyl)-diphenyl can also be used with equal success for the manufacture of the compound (11). Instead of sodium methylate, potassium hydroxide (KOH content about 90%) can equally well be used as the alkaline condensation agent.

4,4'-bis-(dimethoxyphosphonomethyl)-diphenyl and 2-chlorobenzaldehyde can also be initially introduced as a solution in dimethylformamide, and the sodium methylate introduced at the reaction temperature, either as a solid or as a suspension in dimethylformamide.

Equally, instead of using solid sodium methylate, a solution thereof in methanol can be used. Finally, dimethyl-

sulphoxide is also suitable for use as a solvent instead of dimethylformamide.

The distyryldiphenyl compounds of the formula

listed in the table below can be prepared in a similar manner.

Number	R	Melting point, ° C.
13		>300
14		254-255
15		258-259
20		240-241
16		246-247
25		266
17		246-247
30		246-247
35		>300
19		240-241
20		220-221
40		259-260
21		194-196
45		180-181
22		>300
50		194-196
24		180-181
55		220-221
25		259-260
60		220-221

EXAMPLE 2

18 g. of sodium methylate are dissolved in 75 ml. of anhydrous dimethylformamide. To this solution, at 20 to 40° C., is added dropwise, over the course of half an hour, a solution of 51.8 g. of 4,4'-bis-(dimethoxyphosphonomethyl)-diphenyl and 40.2 g. of 4-methyl-2/3-chlorobenzaldehyde (isomer mixture of the 2-chloro-3-chloro derivative in the molar ratio of 45:55) dissolved in 200 ml. of anhydrous dimethylformamide, which is at 60° C., and thereafter the whole is warmed to 40-45° C. After 3 hours at this temperature, the mixture is poured out into 800 ml. of water and the small excess

of alkali is neutralised with acetic acid. The product which precipitates is filtered off and washed with water. After drying, the crude product is purified in respect of colour by dissolving it in chlorobenzene, decolorising with fuller's earth, and adding a two-fold volume of alcohol. The precipitating material is filtered off after cooling in ice, and is dried. 36.5 g. of a product are thus obtained, consisting of a mixture of the following three isomers, and melting at between 205 and 310° C. to give a slightly cloudy melt:

The chloro-methyl-benzaldehyde used as the starting product is obtained by partial oxidation of *o*-chloro-*p*-xylene according to J. Org. Chem., 27, 3705 (1962), the aldehydediacetate being saponified directly, without purification, to give the aldehyde isomer mixture. Purification is effected by steam distillation, with subsequent distillation (boiling point $_{12}=105-112^{\circ}$ C.).

EXAMPLE 3

A polyester fabric (for example "Dracron") is padded at room temperature (about 20° C.) with an aqueous dispersion which per litre contains 0.1 to 1 g. of one of the compounds of the formula (11), (13), (14), (15), (16), (17), (18), (20), (21) or (22) and 1 g. of an addition product of about 35 mols of ethylene oxide to 1 mol of octadecyl alcohol, and dried at about 100° C. The dry material is subsequently subjected to a heat treatment at about 220° C. for 30 seconds. The polyester fabric treated in this way shows a strong optical brightening effect.

EXAMPLE 4

10,000 g. of a polyamide, manufactured in a known manner from hexamethylenediamine adipate, in chip form are mixed with 30 g. of titanium dioxide (rutile modification) and 5 g. of one of the compounds of the formula (11), (13), (14) or (15) in a tumbler vessel for 12 hours. The chips treated in this way are fused in a kettle, heated by oil or diphenyl vapour to 300-310° C., after having displaced the atmospheric oxygen by steam, and the melt is stirred for half an hour. It is then extruded through a spinneret under a nitrogen pressure of 5 atmospheres gauge, and the filament spun in this way is cooled and wound on a spinning bobbin. The filaments produced show an excellent brightening effect of good fastness to washing and to light.

If, instead of a polyamide manufactured from hexamethylenediamine adipate, a polyamide manufactured from *ε*-caprolactam is used, similarly good results are obtained.

EXAMPLE 5

100 g. of polyester granules of terephthalic acid ethylene glycol polyester are intimately mixed with 0.05 g. of one of the compounds of the formula (11), (13), (14), (15) or (16) and the mixture is fused at 285° C., whilst stirring. After spinning through customary spinnerets, strongly brightened polyester fibres are obtained.

EXAMPLE 6

10 An intimate mixture of 100 parts of polyvinyl chloride, 3 parts of stabiliser (Adyastat BD 100; Ba/Cd complex), 2 parts of titanium dioxide, 59 parts of dioctyl phthalate and 0.01 to 0.2 part of one of the compounds of the formula (11), (15) or (16) is rolled to give a film on a calender at 150 to 155° C. The opaque polyvinyl chloride film thus obtained has a substantially higher white content than a film which does not contain the optical brightener.

EXAMPLE 7

20 100 parts of polystyrene and 0.1 part of one of the compounds of the formula (11), (14) or (18) are fused for 20 minutes at 210° C. in a tube of 1 cm. diameter, with exclusion of air. After cooling, an optically brightened polystyrene composition of good fastness to light is obtained.

What is claimed is:

1. A new styryl compound, symmetrically substituted relative to the diphenyl grouping, of the formula

35

40 wherein one, two or three of the symbols R₁, R₂, R₃ and R₄ represent halogen atoms of the group fluorine, chlorine or bromine, whilst the remainder of these symbols denote hydrogen.

2. A new styryl compound according to claim 1, which corresponds to the formula

wherein two or three of the symbols R₅, R₆, R₇ and R₈ represent a halogen atom from the group fluorine, chlorine or bromine, whilst the remainder of the symbols denote hydrogen.

3. Process for the manufacture of a compound of the formula

wherein one, two or three of the symbols R₁, R₂, R₃ and R₄ represent halogen atoms of the group fluorine, chlorine or bromine, whilst the remainder of these symbols

11

denote hydrogen, characterised in that a compound of the formula

is reacted in a solvent and in the presence of a strongly basic alkali compound, in a molecular ratio of 1:2, with a compound of the formula

wherein, in these formulae, R₁, R₂, R₃ and R₄ have the above-mentioned meaning and one of the symbols Z₁ and Z₂ denotes a O=CH— group and the other denotes one of the groupings of the formulae

10

20

25

12

wherein R represents an optionally substituted alkyl radical (preferably with up to 6 carbon atoms), an optionally substituted phenyl radical, a cyclohexyl radical or an aralkyl radical.

4. A compound according to claim 1 in which the halogen is chlorine.

5. A compound according to claim 2 in which the halogen is chlorine.
